METHOD OF FORMING ELECTRODES

Ernest Penker, Flushing, N. Y., assignor to
Etched Products Corporation, Long Island City,
N. Y., a corporation of New York

Application November 6, 1942, Serial No. 464,939

3 Claims. (Cl. 29—155.5)

This invention relates generally to metal stamping and is more particularly directed to a method of producing an electrode from a metal blank in a form to function as a base for supporting a crystal, as used in radio apparatus, for example, in a single stamping operation.

In the use of a piezo crystal, for instance, in the operation of radio apparatus, the crystal is supported on a rigid base of a rectangular shape produced from a metal of the requisite electrical conductivity characteristics, the blank, under present methods of manufacture, being machined, as by a milling operation, to undercut the surface, material being left at each of the four corners to form abutments or shoulders upon which the crystal is to rest, the undercut portion of the surface of the completed electrode being spaced from the shoulder-supported crystal to provide an air space beneath the crystal and permit of polar vibration thereof, between its supported corners. The crystal-supporting shoulders are defined by the meeting side edges of the blank and a connecting arcuate surface in the plane of the peripheral edge of the blank, the meeting edges forming a right angle exterior of the arc. Since the height of the shoulders upon which the crystal is supported, relative to the undercut area between the shoulders, does not exceed two one-thousandths of an inch, it will be evident that the utmost precision is required in setting up the work and in the operation of the milling cutter, by one skilled in milling machine operation, in many instances a final lapping operation being necessary to attain the requisite accuracy in the ultimate product. This makes for high production costs and, under the best of operating conditions, electrodes cannot be turned out with the rapidity that is essential to meet the demands for high speed quantity production.

Therefore, it is the principal object of this invention to provide a method of producing electrodes adapted to function as supporting elements for crystals, as employed in radio apparatus, whereby the electrodes may be rapidly and precisely formed from a blank of metal in a single stamping operation, in a manner to eliminate the necessity for any subsequent machining, thereby materially reducing the cost of the electrodes, and, what is more important, providing for high speed quantity production.

It is also an important object of this invention to provide means for converting a rectangular blank of metal having a true level surface into

5 an electrode or crystal support, by effecting the displacement of material between the corner sections of the blank, in a direction parallel to its axis in a predetermined amount, in a single metal shearing operation under concentrated pressure, the electrode thus produced being in its ultimate form for functioning as a crystal support.

Another objective of my invention is to provide a method, as aforesaid, for producing an electrode from a metal blank, embodying shoulders at the diagonally opposite corners thereof and a depressed major surface between the shoulders by effecting a uniform displacement 10 of the metal of the blank inwardly of the shoulder-forming surfaces thereof, only in the direction in which the metal displacing pressure is applied to the blank, so that the surfaces of the shoulders which are parallel to the outer periphery of the blank will meet the surface formed 15 by the bodily displacement of the metal therebetween at a cleanly defined angle of 90°, as might be obtained in a carefully executed milling operation, this result being attained by restraining the metal against the lateral flow or movement under pressure that occurs in the conventional so-called coining operation.

Other objects and advantages which flow from the practicing of my invention will become manifest as the description proceeds and I would have it understood that while I have elected to confine this disclosure to the production of an electrode of a specific conformation, as used for a particular purpose, my invention may be utilized 20 in the manufacture of electrodes or base-forming elements of the same general characteristics, for other purposes.

In the accompanying drawing, I have shown a 25 specific form of electrode which may be produced by my method, together with an arrangement of mechanism or means whereby my method may be carried into effect, it being evident that the shape of the electrode or end product obtained in the practicing of my method may vary from that herein shown, as may be predetermined by the shape of the coacting forming means.

In the drawing—

Figure 1 is a plan view of a blank from which the electrode is formed in a single operation.

Figure 2 is a plan view of the completed electrode, embodying a shoulder at each corner, formed by the displacement of the metal therebetween in a shearing operation.

Figure 3 is a diagonal sectional view, on a magnified scale, on the line 3-3 of Figure 2.

Figure 4 is a fragmentary plan view of the lower part of the mechanism, showing the insert or female die section and the work-retaining nest elements, magnified for clarity; and

Figure 5 is a sectional elevation along line 5-5 of Figure 4, of the coating elements of a mechanism for practicing my invention.

Referring now to the drawing in detail, in which like characters of reference are employed to designate similar parts in the several views, the blank, indicated at 10 in Figure 1, which is rectangular in shape, is punched out of sheet or strip material of the appropriate thickness, the surface which is to be processed in the shearing operation being lapped to render it perfectly smooth and insure absolute uniformity of the cross-sectional area of the blank.

The lapped blank is then located within a nest of a contour complementary to the peripheral edge 11 of the blank and supported from beneath in juxtaposition to the four corners thereof by appropriately formed surfaces of the bed carrying a female die element, the same, as mounted, being depressed against such corner supporting surfaces to provide an area between the corners of the blank in which the latter is unsupported, for the performance of the shearing operation, as hereinafter explained. The displacement of the metal is effected under pressure applied to the upper surface of the blank in the direction of the aforesaid depressed female die element, to form the shoulders 12 and the depressed area 13 therebetween. As will be observed, each of the four shoulders is defined by an arcuate surface 14 in the plane of the peripheral edge of the blank, the edge portions 11a, 11b, connected by said arcuate surface 11c, meeting at a right angle exterior of the latter, as will be apparent.

The aforesaid depressed area 13 between the shoulders 12 of the electrode is formed by the uniform displacement of the metal of the blank solely in the direction in which the displacing pressure is applied, in a predetermined amount, as for example, two-thousandths of an inch, the vertical arcuate surfaces 14 of each of the shoulders 12 meeting the horizontal depressed surface 13 at an angle of 90° throughout its length. In this controlled and uniform displacement of the metal only in the direction in which the displacing pressure is applied to the blank, an amount equivalent to the material displaced between the shoulders 12 is extruded from the opposite or under surface of the blank, as indicated at 15, within the unsupported area thereof, in the practicing of my method, as by the means hereinafter described. The resulting end product is precisely dimensioned to efficiently perform its intended function as a crystal support, no subsequent lapping or machining operations being required to condition it for use.

As shown in Figures 4 and 5, a conventional punch press or stamping machine may be employed in practicing my method, the general construction and mode of operation of which is well known and, in view of which, I have illustrated only so much of the machine structure as is essential to a clear understanding of the procedure which I follow in conditioning the mechanism for carrying my method into effect.

As herein shown, the mechanism includes a male punch or die 20 carried by the usual central slide or ram, with which the head 21 is movable, a pressure plate 22 being suspended

from the head by screws 23 for relative vertical movement under the influence of and in opposition to the coil springs 24 within bores 18 and 19, the heads of the screws 23 being vertically movable within the counterbores 17 of the head, to provide for movement of the pressure plate toward the head in the progression of the punch or male die 20 to its work-engaging position, as will be explained.

A bed 25 is recessed as at 26 for the reception of an insert or female die element 27 of circular cross-section, which is mounted below the surface of the bed to form a central vertical depressed area 27a, the surfaces of the bed bounding the depressed area at the four corners of the insert and indicated at 27b, functioning to support the blank at its respective corners and to cooperate with the male die and the surface of the pressure plate contiguous thereto, in the formation of the shoulders 12 of the electrode, the metal displaced in the latter operation, indicated at 15, entering into the recess 26 above the insert or die element within the area depressed 27a. A so-called nest, which may be of a unitary or sectional construction, and indicated at 28, is fixed to the upper surface of the bed 25 by the screws 29 or other suitable media.

The nest 28, as will be apparent, defines the work position and provides an opening 28a complementary at its corners to the contour of the blank forming the work, and having recesses 28b above the non-effective peripheral segments 33a of the die 27, with its four corners abutting upon the aforesaid bounding surfaces 27b for the insert or die element 27, the unsupported under surface of the blank being disposed in vertical spaced relation to the depressed area 27a of said die element, as shown in Figure 5.

As will be noted, the pressure plate 22 is recessed, as at 30, to register with the opposed surface of the nest 28 in the descent of the central slide, the base of the recess being countersunk, as at 31, for the reception of the heads of the nest-securing screws 29. The height of the nest-forming members is approximately one-half of the thickness of a blank disposed in the nest opening 28a, the recess 30, in the head 22 complementary to the nest, being of a corresponding depth for accurate registration of the opposed surfaces. The surface surrounding the male die position of the pressure plate 22 is recessed as at 32 to provide for the cooperation of the male die with the female die element 27, the depth and area of such recess corresponding to the height and area of the peripheral edge of the blank as exposed above the nest 28, the effective surface of the male die or punch 20 being of the same cross-sectional area and configuration as the insert or female die 27.

For performing an electro-forming operation, the work, indicated at w in Figure 4, is located in the nest opening 28a, with its corners abutting upon the surfaces 27b bounding the female die 27, and spanning the depressed or undercut area 27a thereof, the height of the corner-engaging surfaces 27b bounding the female die element relative to the central depressed area 27a thereof, being accurately proportioned to provide for the displacement of the necessary metal under the pressure of the male die in the formation of the electrode. As the central slide descends, it will be manifest that the pressure plate 22, suspended from the head 21, will abut upon the opposed surface of the bed 25

with its recess 30 in registration with the nest 28 and the inner recess 32 in registration with the cooperating surfaces of the work in the nest opening 28a. The initial downward movement of the central slide will compress the springs 24, the head 21 impinging upon the pressure plate 22 to urge it toward the bed 25 to firmly clamp the work between the opposed cooperating surfaces bounding the die element 27 and the pressure plate. In appropriately timed relation to the application of the clamping effort to the work, as just described, the male die or punch 20, in the continuing descent of the central slide, impinges upon the work to effect the displacement, by shearing action, of the metal within the unsupported area of the blank, as defined by the coacting surfaces of the two die elements, in the direction of movement of the male die, to extrude the excess metal in the same direction into the depressed area 27a of the female die element 27, in the completion of the electrode-forming operation.

Since the male die 20 is of the same diameter and cross-sectional configuration as the female die element or insert 27, the effective vertical surfaces thereof forming a true right angle with their horizontal surfaces, the direction of movement of the metal in its displacement under pressure of the impinging male die or punch 20 is positively controlled, the vertical surfaces at the die position coacting to direct the metal in its displacement in a path parallel to the axis along which the pressure is applied thereto, and effectively preventing lateral flow or spreading, as obtains in the usual coining operation. Obviously, by restraining lateral flow or displacement of the metal, as it is compacted under the punch pressure, it can yield only in the direction of movement of the punch for final displacement into the area 27a of the female die 27, the demarcation between the vertical arcuate surfaces 14 of the shoulders 12 of the electrode and the horizontal depressed area 13 formed therebetween in the displacement of the metal, being sharply and cleanly defined, as a result of the shearing action induced by the coacting male and female die surfaces, the curved surfaces of the crystal-supporting shoulders meeting the horizontal surface 13 at an angle of 90°, it being understood, of course, that the arcuate surfaces 14 of the respective shoulders are complementary to the vertical surfaces of the male die which are effective in the formation of the shoulders, in the metal displacing operation.

As previously pointed out, the depth of the surface 13, relative to the parallel plane of the shoulders 12, at the corners of the electrode, is usually about .002 of an inch, so that it will be apparent that in order to provide the necessary clearance between a crystal mounted upon the shoulders 12 and the depressed area 13 of the electrode, absolute precision in the gauging of the surface 13 below the crystal-engaging top surfaces of the shoulders is not essential, but the vertical surfaces of the shoulders must meet the horizontal surface 13 at a sharp angle, such as I obtain in the practicing of my method, to insure a uniform spacing of the crystal relative to the depressed surface 13, throughout the area in which the crystal is unsupported, to admit of the vibration of the crystal in performing its intended function when supported by the electrode. Obviously, were it attempted to produce an electrode in accordance with the usual coining operation, such essential condition could not obtain,

as the lateral flow of the metal in its displacement would build up the density thereof in the area of the jointure of the vertical surfaces of the shoulders with the horizontal depressed surface therebetween, with the result that there would be a lack of uniformity in the relative vertical spacing of the unsupported area of the crystal and the opposed electrode surface 13, with the attendant inefficiency in the functioning of the crystal and the apparatus of which it may be an important element. By my method, uniform spacing of the unsupported area of the crystal relative to the area 13 of the electrode is assured, together with perfect performance of the crystal and the electrically coacting electrode.

Manifestly, the height of the shoulders 12 may be varied, as may be predetermined, to meet operational requirements, such changes in dimensions in the completed electrode as may be requisite for a particular service being effected in the practicing of my invention, by employing co-operating dies and work-retaining means of the appropriate sizes and configuration, for turning out the work in the manner hereinbefore set forth.

Although the pressure plate, as shown in the preferred adaptation of this invention, has been provided with a recess 32, for registration with the exposed surface of the blank w, it is within the province of this invention to eliminate this particular guide mechanism so long as the blank is firmly nested in relation to the female die 27 and the male puncher die 20 is in alignment for cooperation with the female die as aforesaid.

I claim:

1. A method of forming an electrode for supporting a crystal or the like in the functioning of radio apparatus, which comprises forming a rectangular blank, immovably supporting said blank at its diagonally opposite corners, applying pressure to the surface of the blank in the area of its unsupported portion defined by said corners to displace the metal constituting said unsupported portion, in a shearing action, to a position below the corners, and simultaneously restraining the metal from spreading laterally in its displacement under pressure to form diagonally opposite vertical abutments defining a depressed area therebetween.

2. A method of forming an electrode for supporting a crystal in the functioning of radio apparatus, which comprises forming a rectangular blank, immovably supporting the diagonally opposite corner portions of said blank in a horizontal plane, applying vertical pressure to the surface of the blank in the area of its unsupported portion defined by the immovably supported corner portions, to displace the metal constituting said unsupported portion to a position below that of the corner portions in a plane parallel thereto, and simultaneously controlling the displacement of the metal to prevent lateral spreading thereof under pressure, to form a horizontal surface in depressed parallel relation to surfaces of the corner portions and diagonally opposite vertical surfaces meeting such horizontal surface at an angle of 90°.

3. A method of forming an electrode from a rectangular blank, for supporting a crystal in the functioning of radio apparatus, which consists in immovably supporting the corner portions of the blank, applying pressure to the surface of the blank, in the area of the unsupported

portion thereof defined by said immovably supported corner portions, in a direction perpendicular to the plane of the surface of the blank to displace the metal constituting said unsupported portion relative to the corner portions, in a shearing action, and simultaneously confining the displacement of the metal to a path parallel

5 to the axis along which the pressure is applied, to form abutments at the corners of the blank and a depressed surface therebetween, in a plane parallel to the plane of the corner portions, said depressed surface meeting surfaces of the abutments at an angle of 90°.

ERNEST PENKER.
